UNITED STATES PATENT OFFICE

JOHN H. WILHELM, OF ROCKAWAY BEACH, NEW YORK, ASSIGNOR, BY MESNE ASSIGNMENTS, TO MARGON CORPORATION, OF NEW YORK, N. Y., A CORPORATION OF NEW YORK

EYE SET FOR DOLLS

Application filed May 2, 1930. Serial No. 449,167.

This invention relates to movable eyes for dolls, and more particularly to such eyes which are manually operable.

A manually operable eye set is disclosed in the patent to John H. Wilhelm, 1,658,471, issued February 7, 1928. Such an eye set is both theoretically and practically operative and successful, but suffers from the disadvantage that it is difficult to mount the same within a doll's head or similar toy figure. This problem of making possible a secure and permanent mounting which may be applied accurately in place in a rapid and economical manner has proven troublesome even in the case of gravity operated eye sets, and experience has shown that for wide commercial adoption, an eye set must fulfil the following desiderata.

In the first place, the eye set itself as an article of manufacture should be simple and economical in construction so that it may be sold to doll manufacturers at a cheap price. Secondly, the mounting, when in place, must be secure and fool-proof so that the doll can be roughly treated and thrown around without dislodging the eye set. Thirdly, the entire movable eye system should be arranged to permit mounting of the same within the doll's head through the neck of the head, so as to dispense with the necessity of cutting open the top of the head and thereafter using a wig to conceal the resulting disfigurement. Fourthly, even though the eye set is mounted through the neck opening it must be accurately positioned within the head so that the eyes will fit the eye sockets closely.

These, and other desiderata of the same general character have led to the wide adoption of eye systems in which the eye set is supported on a cross bridge or other suitable supporting means provided with relatively movable prongs which may be imbedded in the material of the doll's head after locating the same in proper position by applying the eye set directly to the eye sockets of the head.

A typical example of such an eye set and of a tool for mounting the same within a doll's head are, respectively, disclosed in

patents to Alexander Konoff, 1,621,072 and 1,621,073, both issued March 15, 1927, and this general class of movable eye systems has in the commercial field almost wholly displaced eye systems involving the screwing or cementing of the eye set support within the head in the manner disclosed, for example, in the aforesaid patent to Wilhelm.

The primary object of the present invention is to fulfil the foregoing desiderata and to provide a manually operable movable eye set which can be economically manufactured, and readily and accurately and securely inserted within a doll's head through the neck thereof.

The manually operable system, unlike the gravity operated system, necessitates the use of a control member which projects at some point from the doll's head. This member must not interfere with the normal insertion and mounting of the system within the head, and yet must be brought into operative engagement with the eye set. To make this possible is another object of this invention, which is accomplished by making at least a portion of the control member resilient to facilitate placing the same in the desired position in the doll's head after the eye set has been located.

It is of advantage for obvious reasons to make the eye set movable under gravity control as well as manual control, so that the advantages of both may be obtained. In fact the manual control is of even greater advantage when used conjointly with gravity control, because it makes it possible for the child using the toy to simulate life-like conditions to great advantage, for when the doll is reclining and apparently sleeping, the child may cause the eyes of the doll to open upon touching or lifting the same, and before the doll is turned to an upright position; and the converse is true when the doll is at first erect. Accordingly, a further object of the present invention resides in the provision of a gravity and manually operable movable eye system characterized by the advantages outlined above.

Still another object of my invention is to provide a movable tongue and eye system in

so that a doll's head having a mouth opening may be provided with a movable tongue operable either manually or by gravity, or both. It is desirable that the addition of 5 the movable tongue be possible through the neck of the doll's head and without interfering with the mounting and assembly of the gravity and manually operable movable eye system previously outlined, and to so do 10 is another object of the present invention.

To the accomplishment of the foregoing and such other objects as will hereinafter appear, my invention consists in the gravity and manually operable movable tongue 15 and eye system elements and their relation one to the other as hereinafter are more particularly described in the specification and sought to be defined in the claims. The specification is accompanied by drawings in 20 which:

Fig. 1 is a section through a doll's head fitted with one form of the present invention;

Fig. 2 shows the same with the eyes in 25 open position;

Fig. 3 is a partially sectioned rear elevation of the head;

Fig. 4 is a section taken through a doll's head fitted with a modified form of my invention;

Fig. 5 is a section in plan of the same;

Fig. 6 is a partially sectioned rear elevation of the head;

Fig. 7 is a detail showing the engagement 35 of the control member with the eye set;

Fig. 8 is a section taken in the plane of the line 8—8 in Fig. 9;

Fig. 9 is a section taken in the plane of the line 9—9 in Fig. 10; and

Fig. 10 is a section similar to that shown 40 in Fig. 4, showing the manner in which a movable tongue may be added to the eye system.

Referring to the several forms of the invention disclosed, in each case there is provided an eye set A held in place by supporting means B provided with relatively movable prongs imbedded in the material of the doll's head. A manually operable member 45 C is arranged to control the movement of the eye set A, and at least a portion D of said control member is made resilient to facilitate placing the same in a desired position in a doll's head.

Referring now to the form of the invention disclosed in Figs. 1, 2, and 3, the eye set A comprises eyes 12 mounted on a cross rod 14. The supporting means B for the eye set comprises a cross bridge 16 in which the plates 18 fitted with prongs 20 are slidably mounted, so that by moving the plates 18 outwardly, the prongs 20 may be imbedded in the material of the doll's head. The supporting means B is similar to that 60 shown in Fig. 5, and referring to that, as

well as to Fig. 1, it will be seen that the bridge 16 is provided with forwardly projecting arms 22 having slots 24 in which the cross rod 14 is journaled. A spring 26 is arranged to resiliently urge the cross rod 14, and with it the eyes 12 toward the eye openings or eye sockets in the doll's head.

The cross rod 14 has affixed thereto, preferably by welding, a depending weight 30 for gravity control of the eyes, and an arm 32 for manual control of the eyes. The arm 32 is preferably provided by simply extending the weight arm upwardly, and the resulting upward extension 32 is so bent or positioned that it acts as a stop to limit the closing movement of the eyes by contacting with the inner wall of the doll's head, as is best shown in Fig. 1. The opening movement of the eyes is limited by contact of a buffer 34 mounted in the weight 30 with the portion 36 of the doll's head.

A control opening 40 is provided in the doll's head and preferably at the back of the neck thereof out of which the handle or button 42 of the control member C projects for manual operation. A preferably resilient wire or rod 44 interconnects the handle 42 with the eye set A, and more particularly with the arm or upward extension 32. In the present case, the arm 32 and the wire 44 are each bent into the form of a ring, and the rings are pivotally secured together by a rivet 46. The operation of the device is obvious from the drawing, the gravity control normally prevailing, but manual control against the gravity control being available by manipulation of the handle 42.

The manner in which the eye set of the present eye system is placed within the head of the doll is exactly like that used with a simple gravity eye system of analogous type. More specifically, the supporting means B of the present invention closely resembles that disclosed in the Konoff patents previously adverted to, and it may be mounted within the head by placing the same on a tool such as is described in the said Konoff patents, slipping the head of the doll over the end of the tool and the eye set, and placing the eye openings of the head carefully on the eyes and thereafter operating the tool to force the prongs 20 into the material of the doll's head. The head may then be removed from the tool, at which time the wire 44 and the handle 42 will be located in the neck of the doll's head. The wire 44 being resilient, the handle 42 may be forced upwardly until opposite the control opening 40, in order to place it in the operative position shown in the drawings.

The arrangement so far described may be mounted in place in another manner which consists, essentially, in letting the control member C hang loosely from the eye set

while the latter is on the mounting tool, next passing the handle 42 through the control opening 40 in the back of the neck of the head, and thereafter oscillating the head 5 upwardly so as to move the neck of the head around the tool into final position with the eyes in place. This method has the advantage of making it unnecessary for the wire 42 to be resilient, but on the other hand, has 10 the disadvantage of slowing up the operation of mounting the eye mechanism within the head.

A modified control mechanism for the eye set is disclosed in Figs. 4-8 of the drawing. 15 Referring to these figures, it will be observed that the eye set A and supporting means B therefor are identical with those already described in connection with Figs. 1-3. However, the arm for carrying the 20 pendant or gravity weight 30 is extended upwardly past the cross rod 14 to form an arm 50 which is affixed to the cross rod 14 and which is suitably bent so that the upper end 52 thereof acts as a stop to limit the 25 closing movement of the eye set, as is best shown in Fig. 10.

The control member C comprises a strip of metal 54 which carries a control handle 56 at one end thereof and is arranged at the 30 end D thereof for resilient or snap engagement with the arm or upward extension 50. The arrangement is such that the eye set is mounted within the doll's head without the manual control member C being attached 35 thereto so that the mounting problem is reduced simply to that of mounting a gravity controlled eye set in the doll's head. The manual control member C is thereafter pushed through the opening 40 in the back 40 of the neck of the head until the resilient bifurcated end D of the strip 54 snaps into engagement with the arm 50. This mode 45 of attachment is a very speedy one for obvious reasons, and possesses the additional advantage that the handle 56 may be designed in any manner desired without the requirement that it be able to pass through the control opening 40. In fact a simple slit 50 may be provided through which the strip 54 may pass, and the end of the strip may be bent as desired to form a control handle.

The manner in which the desired locking engagement of the eye set A and the control 55 member C is obtained is best shown in detail Figures 7 and 8, referring to which it will be seen that the arm or upward extension 50 is pressed to take the cross section shown in Fig. 8 at the region engaged by the strip 54. The end of the strip 54 is stamped out to form a slot 58 closed at the outer end by hooks 60 which may spread apart by inwardly directed pressure due to the convergent slope of the sides of the slot-approaching 60 hooks 60. It is clear from Fig. 8 that by

pushing the strip 54 against the extension 50, the hooks 60 may be forced past the same and into permanent holding relation therewith. The slot 58 is made relatively short so as to avoid excess lost motion, but is sufficiently long to accommodate the change in angularity between the arm 50 and the strip 54 when the eyes move between the open and closed positions. The arm 50 is keyed or upset to make the fins 53 indicated in Fig. 7 at a point just above that engaged by the strip 50 in order to guard against the possibility of the strip 54 being pulled off the end of the arm 50.

The modification of my invention just described is preferred not only for its inherent advantages already mentioned, but also because it makes possible the addition of a movable tongue to the mechanism so far described. This arrangement is illustrated generally in Fig. 10 which coincides substantially with Fig. 4 but differs therefrom in that the doll's head is provided with a mouth opening 70 in which, or just in back of which, a tongue 72 is positioned. The tongue 72 is held by supporting means 74 preferably rigidly affixed to the strip 54, so that the manually operable eye system already described provides the sole support and operating means for the tongue 72.

In order to retain the simplicity of attachment of the system, the tongue and tongue supporting means are preferably inserted through the neck opening, and affixed to the strip 54 after the latter has been placed in position. The manner in which this is done is clearly evident from Figs. 8 and 9 showing the strip 54 to be provided with a pair of marginal indentations 76 the length of which is equal to the width of the supporting means 74, while the supporting means 74 is shown to comprise a pair of resilient reciprocable side members the upper ends of which are bent to form recesses 78 and convergent faces 80 leading thereto. To add the movable tongue to the eye system, it is merely necessary to insert the tongue and supporting means through the neck of the doll and push the faces 80 against the strip 54 at the marginal indentations 76 until the support 74 snaps into holding relation. The recesses 78 grip the edges of the strip 54 while the indentations 76 prevent sliding movement of the support 74 along the strip 54. Movement of the eye set 100 whether caused by gravity or manual operation is accompanied by a movement of the tongue 72 which enhances the realism of the toy. Movement of the pendant weight 30 is not interfered with by the tongue supporting means 74, because the weight may oscillate freely between the sides of the tongue 105 supporting means.

The construction of my gravity and manually operable movable tongue and eye sys- 130

tem, the method of applying the same to a doll's head, and the many advantages thereof, will, it is thought, be apparent from the foregoing detailed description. The eye set and supporting and mounting means therefor may be almost identical with known standardized types, and retains all of the advantages thereof, such as accuracy of location, permanence of mounting, resilient movement of the eyes toward the eye openings, and ease of insertion and attachment through the neck of the doll's head. The manual control member is exceedingly simple, from an apparatus standpoint, is located at an inconspicuous part of the head ordinarily concealable by clothing, and may be readily placed in the desired operating position, this latter feature being facilitated by making at least a portion of the control member resilient. The movable tongue system also is structurally simple and applicable to the doll's head through the neck-opening and without sacrifice of the advantageous features of the movable eye system. Either the eye or the tongue and eye system may readily be made gravity as well as manually operated, and when this is done, a simple upward extension of the pendant weight arm acts both as an operating arm for manual operation of the eye set, and as a stop for limiting the movement of the eye set.

It will be apparent that while I have shown and described my invention in the preferred forms, many changes and modifications may be made in the structures disclosed without departing from the spirit of the invention defined in the following claims.

I claim:

1. In combination, a doll's head having eye openings, a neck opening and a control opening located at the back of the neck portion of the head, and a gravity and manually operable movable eye system arranged to facilitate insertion thereof in the openings of said doll's head comprising an eye set, means for supporting the same including separable prongs imbedded in the material of the doll's head and means resiliently urging said eye set toward said eye openings, a gravity weight attached to said eye set and having an upward extension acting as a stop to limit the movement of the eye set, and a manually operable arm connected to said upward extension and extending through said control opening.

2. In combination, a doll's head having a neck opening and having a control opening located at the back of the neck portion of the head, and a manually operable movable eye system arranged to facilitate insertion thereof in the doll's head comprising a movable eye set, means to support the same, an arm on said eye set, and a simple manual control arm including means attached to

said arm and a handle projecting out of the control opening, said control member being made resilient and bendable to facilitate pushing the handle through the neck opening and out of the control opening.

3. In combination, a doll's head having a neck opening and having a control opening located at the back of the neck portion of the head, and a gravity and manually operable movable eye system arranged to facilitate insertion thereof in the doll's head comprising a movable eye set, means to support the same including relatively movable prongs imbedded in the material of the doll's head, a gravity weight on said eye set, an arm on said eye set, and a manual control member including means attached to said arm and a handle projecting out of the control opening, said control member being made resilient and bendable to facilitate pushing the handle through the neck opening and out of the control opening.

4. In combination, a doll's head having eye openings, a neck opening and a control opening at the back of the neck, and a gravity and manually operable movable eye system arranged to facilitate insertion thereof in the finished doll's head comprising a movable eye set, means to support the same including relatively movable prongs imbedded in the material of the doll's head and means resiliently urging the eye set toward the eye openings, a gravity weight arm on said eye set having an upward extension acting as a stop to limit the movement of the eye set, and a manual control member including means attached to said upward extension and a handle projecting out of the control opening, at least a portion of said control member being made resilient and bendable to facilitate pushing the handle through the neck opening and out of the control opening.

5. In combination, a doll's head having a neck opening and an additional control opening, and a manually operable movable eye system arranged to facilitate insertion thereof in the doll's head comprising a movable eye set, means to support the same, an arm on said eye set, and a manual control member including a handle projecting out of the control opening, said arm and control member including and being interconnected by mating snap engagement means, said snap engagement means permitting the control member to be inserted directly through the control opening and pushed into snap engagement with the arm.

6. In combination, a doll's head having a neck opening and an additional control opening, and a gravity and manually operable movable eye system arranged to facilitate insertion thereof in the doll's head comprising a movable eye set, means to support the same including relatively movable

- prongs imbedded in the material of the doll's head, a gravity weight on said eye set, an arm on said eye set, said arm and control member including and being interconnected by mating snap engagement means, and a manual control member including a handle projecting out of the control opening, said engaging means permitting the control member to be inserted directly through the control opening and pushed into snap engagement with the arm. 7. In combination, a doll's head having a neck opening and an additional control opening at the back of the neck, and a gravity and manually operable movable eye system arranged to facilitate insertion thereof in the finished doll's head comprising a movable eye set, means to support the same including relatively movable prongs imbedded in the material of the doll's head, a gravity weight arm on said eye set having an upward extension and a manual control member including bifurcated snap engagement means engaging the aforesaid upward extension and further including a handle projecting out of the control opening, said engaging means being made resilient so that the control member may be inserted directly through the control opening and pushed into snap engagement with the upward extension. 8. In combination, a doll's head having eye openings, a neck opening and an additional control opening at the back of the neck, and a gravity and manually operable movable eye system arranged to facilitate insertion thereof in the finished doll's head comprising a movable eye set, means to support the same including relatively movable prongs imbedded in the material of the doll's head and means resiliently urging the eye set toward the eye openings, a gravity weight on said eye set having an upward extension acting as a stop to limit the movement of the eye set, and a manual control member including bifurcated snap engagement means engaging the aforesaid upward extension and a handle projecting out of the control opening, said engaging means being made resilient so that the control member may be inserted directly through the control opening and pushed into snap engagement with the upward extension. 9. In combination, a doll's head having a mouth opening and a control opening at the back of the neck, and a manually operable movable tongue and eye system comprising a movable eye set, means to support the same, an arm on said eye set, a manual control member attached to said arm and having a handle extending through the control opening, and a movable tongue in said mouth opening directly affixed to said control member. 10. In combination, a doll's head having a mouth opening, a neck opening, and a control opening, and a manually operable movable tongue and eye system arranged to facilitate insertion thereof in a doll's head comprising a movable eye set, means to support the same including relatively movable prongs imbedded in the material of the doll's head, a movable tongue in said mouth opening, a manual control member having a handle extending through the control opening, and snap engagement means operatively connecting the control member and the movable eye set and tongue, said last named means being made resilient to facilitate placing the elements of the system in the desired relation. 11. In combination, a doll's head having a mouth opening, a neck opening, and an additional control opening at the back of the neck, and a gravity and manually operable movable tongue and eye system arranged to facilitate insertion thereof in a doll's head comprising a movable eye set, means to support the same including relatively movable prongs imbedded in the material of the doll's head, a gravity weight arm on said eye set having an upward extension, a manual control member attached to said upward extension and having a handle extending through the control opening, and a movable tongue in said mouth opening directly affixed to said control member. 12. In combination, a doll's head having eye openings, a mouth opening, a neck opening and additional control opening at the back of the neck, and a gravity and manually operable movable tongue and eye system arranged to facilitate insertion thereof in a finished doll's head comprising a movable eye set, means to support the same including relatively movable prongs imbedded in the material of the doll's head and means resiliently urging said eye set toward the eye openings, a gravity weight arm on said eye set having an upward extension acting as a stop to limit the movement of the eye set, a manual control member attached to said upward extension and having a handle extending through the control opening, and a movable tongue in said mouth opening directly affixed to and supported by said control member. 13. As an article of manufacture, a gravity and manually operable movable eye system adapted for insertion into a finished doll's head comprising a movable eye set, means to support the same including relatively movable prongs to be imbedded in the material of the doll's head, a gravity weight arm on said eye set, another arm on said eye set, and a manual control member including a handle, said last mentioned arm and control member including and being interconnected by mating snap engagement means, 14. In combination, a doll's head having a mouth opening, a neck opening, and a control opening, and a manually operable movable tongue and eye system arranged to facilitate insertion thereof in a doll's head comprising a movable eye set, means to support the same including relatively movable prongs imbedded in the material of the doll's head, a movable tongue in said mouth opening, a manual control member having a handle extending through the control opening, and snap engagement means operatively connecting the control member and the movable eye set and tongue, said last named means being made resilient to facilitate placing the elements of the system in the desired relation.

permitting the same to be pushed into locking engagement.

14. As an article of manufacture, a gravity and manually operable movable eye system adapted for insertion into a finished doll's head comprising a movable eye set, means to resiliently support the same including relatively movable prongs to be imbedded in the material of the doll's head, 5 a gravity weight arm on said eye set having an upward extension for acting as a stop to limit the movement of the eye set, and a manual control member including a handle, said arm and control member including 10 and being interconnected by mating snap engagement means, permitting the same to be pushed into locking engagement.

15. As an article of manufacture, a manually operable movable eye and tongue system adapted for insertion into a doll's head comprising a movable eye set, means to support the same, an arm on said eye set, a manual control member including a handle, said arm and control member having mating 20 parts designed to be engaged or attached together by a resilient or snap engagement, a tongue, and means for affixing the same to said control member after the latter has been placed in operative position in the doll's head.

16. As an article of manufacture, a gravity and manually operable movable eye and tongue system adapted for insertion into a finished doll's head comprising a movable eye set, means to support the same including relatively movable prongs to be imbedded in the material of the doll's head, a gravity weight on said eye set, an arm on said eye set, a manual control member including a handle, said arm and control member having mating parts designed to be engaged or attached together by a resilient or snap engagement, a tongue, and means for affixing the same to said control member after the latter has been placed in operative position in the doll's head.

17. As an article of manufacture, a gravity and manually operable movable eye and tongue system adapted for insertion into a finished dolls' head comprising a movable eye set, means to resiliently support the same including relatively movable prongs to be imbedded in the material of the doll's head, a gravity weight on said eye set having an upward extension for acting as a stop to limit the movement of the eye set, a manual control member including a handle, said upward extension and control member having mating parts designed to be engaged or attached together by a resilient or snap engagement, a tongue, and means for affixing the same directly to said control member after the latter has been placed in operative position in the doll's head.

18. In combination, a doll's head having

eye openings, a neck opening and a control opening located at the back of the neck portion of the head, and a gravity and manually operable movable eye system arranged to facilitate insertion thereof in the openings of said doll's head comprising an eye set, means to support the same including means resiliently urging said eye set toward said eye openings, a gravity weight arm attached to said eye set and having an upward extension, and a manually operable arm connected to said upward extension and extending through said control opening.

Signed at New York in the county of New York and State of New York this 29 day of April A. D. 1930.

JOHN H. WILHELM.
